Primary Examiner — Darlington Ly*Assistant Examiner* — Jeremy Koenig(74) *Attorney, Agent, or Firm* — Robert J. Yarbrough of Lipton, Weinberger & Husick(57) **CLAIM**

I claim the ornamental design for a wheel protector, as shown and described.

DESCRIPTION

FIG. 1 is a front perspective view of a new design for a wheel protector;

FIG. 2 is a rear perspective view thereof;

FIG. 3 is front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The ornamental design for the wheel protector that is claimed is shown in solid lines on the drawings.

1 Claim, 6 Drawing Sheets(56)
